US0D1092373S

(12) **United States Design Patent** (10) **Patent No.:** **US D1,092,373 S**
(45) **Date of Patent:** **** Sep. 9, 2025**

(54) **BATTERY**

- (71) Applicant: **LiBEST INC.**, Daejeon (KR)
- (72) Inventors: **Joo Seong Kim**, Incheon (KR); **Seung Gyu Lim**, Daejeon (KR); **Mi Hee Kim**, Daejeon (KR); **Ji Hoon Jang**, Daejeon (KR)
- (73) Assignee: **LiBEST INC.**, Daejeon (KR)
- (**) Term: **15 Years**
- (21) Appl. No.: **29/868,199**
- (22) Filed: **Nov. 23, 2022**
- (51) LOC (15) Cl. **13-02**
- (52) U.S. Cl. **USPC D13/103**
- (58) **Field of Classification Search**
USPC D13/103, 104, 106, 107, 108, 110, 112, D13/118, 119, 184, 199
CPC H02J 7/00; H02J 7/0042; H02J 7/0044; H02J 7/0047; H02J 7/0045; Y02E 60/12; Y02E 60/122; Y02E 60/124; Y02E 60/50; H01M 2/0207; H01M 2/0202; H01M 10/058; H01M 50/553; H01M 4/742

(57) **CLAIM**

The ornamental design for battery as shown and described.

DESCRIPTION

FIG. 1 is a perspective view of a battery showing our new design,

FIG. 2 is a top plan view thereof;

FIG. 3 is a bottom view thereof;

FIG. 4 is a left side view thereof;

FIG. 5 is a right side view thereof;

FIG. 6 is a front view thereof; and,

FIG. 7 is a rear view thereof.

The broken line representations in the figures show unclaimed environment, and thus form no part of the claimed design.
